UNITED STATES PATENT OFFICE

1,926,707

MARINE STOKER INSTALLATION

Edward Wheeler, Aldwych, London, England, assignor to American Engineering Company, Philadelphia, Pa., a corporation of Pennsylvania

Application October 30, 1931. Serial No. 572,135

3 Claims. (Cl. 122—6)

This invention relates to improvements in stoker-fed furnaces of the type disclosed in the U. S. application of Herbert E. Preston, Serial Number 484,425, filed Sept. 25, 1930, and a principal object of the invention is to provide a novel fluid-cooled wall structure so designed as to meet the requirements of marine practice and adapted primarily for use in conjunction with stoker installations of the aforesigned character.

More specifically, an object of the invention is to provide a tubular fluid-cooled wall structure of simplified and exceptionally compact form.

Another object is to provide a tubular fluid-cooled rear wall structure particularly well suited to marine installations of stoker furnaces.

A still further object of the invention is to provide a fluid-cooled wall structure of the stated type having novel means of support providing for free expansion and contraction of the wall due to changing temperature conditions.

The invention further resides in certain novel structural details and mechanical features hereinafter set forth and illustrated in the attached drawings, in which:

Figure 1 is a transverse sectional view of a marine stoker installation including a fluid-cooled wall panel made in accordance with my invention;

Fig. 2 is an enlarged fragmentary sectional view illustrating the detail structure of one of the fluid-cooled wall structures shown in Fig. 1;

Fig. 3 is a rear elevational view of the panel shown in Fig. 2, and

Fig. 4 is a sectional view illustrating another form of fluid-cooled panel made in accordance with my invention.

The installation of mechanical stokers in marine vessels is complicated by several factors of which one is the extremely limited available space, particularly as to head room. For this and other reasons, it has generally been considered that tubular fluid-cooled walls, which are most efficient for stoker-furnace use, were unavailable for marine installations. By the present invention, I have provided a tubular fluid-cooled wall structure which meets all the exacting conditions of marine usage, is extraordinarily compact in form, strong and durable, yet capable of withstanding all the extraordinary strains to which it necessarily is subjected, and in which full provision is made for expansion and contraction due to temperature changes.

With reference to the drawings, the stoker illustrated is of the multiple-retort underfeed type comprising a main fuel-supporting struc-

ture consisting of a series of tuyères 1 and retorts 2 in alternate arrangement, said tuyères and retorts being inclined downwardly from front to rear of the furnace and terminating in a dead plate 4. Immediately below the dead plate is an extension grate 5, below which in turn is the furnace ash pit 3. A primary ram operates in a cylinder 6 to feed fuel from a hopper 7 into the upper end of each of the retorts 2, and a secondary ram or pusher 8 is provided in each of said retorts for aiding in the proper advancement or feeding of the fuel in the latter. Suitable mechanism designated generally by the reference numeral 9 is provided for actuating the main rams and pushers 8, and also for actuating the extension grate 5. In the bottom of the ash pit 3 is a crusher roll 11 which cooperates with a crusher plate 12 to break up the clinkers and large particles of ash deposited in the ash pit, the crusher roll 11 also functioning in the present instance to feed the ash from the bottom of the ash pit outwardly through a side opening 13 into the space exterior of the rear wall 14 of the furnace. In the present instance, the furnace is illustrated as of the double-boiler type employing two complete stoker units in back-to-back arrangement, the rear wall 14 of the one furnace being spaced apart from the rear wall 15 of the other and forming therebetween a space into which the ashes are discharged from the pits 3 and from which the ashes are removed for disposal. The stoker units are essentially the same and corresponding parts are designated by the same reference numerals.

Referring to Fig. 1, it will be noted that the rear wall 14 comprises a lower panel 16 which forms the rear wall of the ash pit 3 and which terminates at its lower edge at the top of the opening 13 through which the ashes are passed as previously set forth by action of the crusher roll 11. The rear wall 14 with its panel 16 is shown in greater detail in Figs. 2 and 3. As therein illustrated, the upper portion of the wall 14 is supported on a transverse beam 17 which in turn is supported at its ends upon upright beams 18. The panel 16 is suspended immediately below the beam 17 and the upper wall portion and fills the space between the lower edge of this latter portion and the upper edge of the ash discharge opening 13. The panel 16 comprises an upper header 21 and a lower header 22 connected together through the medium of a series or row of tubes 23. The headers 21 and 22 and the connecting pipes 23 are connected in a circulating fluid system through a pipe 24 entering one end of the upper header 21 and a pipe 25 entering

the opposite end of the lower header 22. The panel structure further comprises a series of facing elements or blocks 26 which are held in contact with the tubes 23 by means of clamps 27 which engage the opposite sides of the tubes together with bolts or studs 28 which are secured in the blocks and which pass between adjacent tubes and through the clamps 27 and are secured to the latter by nuts which engage the outer faces 10 of the clamps. These blocks 26 form the effective wall surface of the panel 16. Blocks of this general character and their associated clamps are illustrated in U. S. Patent No. 1,719,642. It will be noted that the lowermost series of facing blocks 15 26' are formed to embrace the inner face of the lower header 22, each block having a depending front portion designated 29 which passes downwardly over the face of the header. These blocks are secured in position in the same manner as 20 the other blocks and as described above.

The panel structure 16 is suspended adjacent its upper end upon a transverse beam 31 extending between the upright beams 18. This beam 31 has a projecting shoulder 32, formed in the 25 present instance by an angle bar secured to the beam, upon which rests and to which is secured by bolts 33 an angle bar 34, one leg of this bar being secured to the panel structure by means of the bolts 28 which secure the upper series of 30 facing blocks 26 to the tubes. It will be noted that the panel is slightly inclined to the vertical, and the lower depending portion of the panel is held in position through the medium of an angle bar 35 secured between the upright beams 18 35 one leg of which extends downwardly between tongues 36 and 37 extending upwardly from an angle bar 38 secured to the panel structure by the bolts 28 which secure one of the lower series of facing blocks to the tubes. This arrangement 40 has the effect of securely anchoring the lower depending portion of the panel in the normal position while at the same time providing for free expansion of the panel longitudinally of the tubes.

In the present instance, the space between the 45 bottom of the upper wall portion and the upper header 21 is filled by a suitable refractory cement 39 which is held in position by flanges 41 depending from the under side of the upper wall portion and flanges 42 projecting from the inner face 50 of the upper header 21. Since the upper header is fixed substantially rigidly with respect to the fixed portions of the wall, there is no tendency for this packing cement to become loose. In the present instance also I have shown the outer face 55 of the panel covered with a layer of suitable asbestos or other cement 43 which is supported in position by the various flanges and beams described above and by a projecting flange 44 intermediate the top and bottom of the panel.

60 The panel structure described above is extremely simple in form, is structurally strong and durable, includes provision for expansion and contraction due to varying temperature conditions, and is highly efficient in its function.

65 Referring to Fig. 1, it will be noted that the space intermediate the walls 14 and 15 and designated by the reference numeral 45 constitutes an ash-removing space, and also provides for free access to the outer faces of each of the walls 70 14 and 15. The fluid-cooled lower portion of the latter wall while being in principal similar to that previously described differs somewhat in detail and constitutes in effect a modification of the fluid-cooled panel previously described. As in 75 the previous instance, the upper portion of the

wall 15 is supported by a transverse beam 46, and a fluid-cooled panel 47 positioned below the lower edge of the upper wall portion fills the space between this upper portion and the upper edge of the ash discharge opening 48. In the present instance, an outer crusher plate 49 is provided in conjunction with the crusher rolls 11, this plate being located directly below the lower edge of the panel 47. The panel which comprises essentially the same construction as that of the panel 16 includes an upper header 51, a lower header 52, and a row of pipes 53 which connect these headers. The panel is connected in a circulating fluid system through a pipe 54 communicating with the upper header and a second pipe 55 communicating with the lower header. Facing blocks 56 are secured against the inner faces of the tubes, to form the effective wall surface of the panel, by means of bolts 57 and clamps 58 similar to those previously described. The lower series of blocks 56' are formed with depending aprons which terminate above the top of the crusher plate 49, and it will be noted that in this instance the lower portions of the tubes 53 are turned rearwardly into the header 52 substantially at right angles to the line of the upper or main portions of the tubes 53. This panel structure is suspended from a transverse beam 61 through the medium of the bolts 57 which secure the upper series of plates 56 to the tubes. The 100 lower depending portion of the panel is held in position through the medium of pins 62 which extend downwardly from the bank of tubes to which said pins are secured by means of studs 63 and clamping bars 64 and 65. These pins 105 pass through apertures in the flanged top of a beam 66 mounted below the panel structure, the arrangement being such that while the panel is free to expand longitudinally of the tubes 53, transverse displacement of the lower end of the 110 panel from the normal position is prevented. The upper flanged end of the beam 66 is confined between bars 67 and 68 depending from the bottom of the panel structure, and the intermediate space is filled with a suitable packing material 115 69 which creates an effective seal at this point. The back of the panel is lined with an asbestos or other suitable cement 71, as in the embodiment 120 previously described, as also is the space between the upper header 51 and the bottom of the upper 125 wall portion.

The construction described above not only forms an efficient fluid-cooled wall structure for the stoker but in the double furnace arrangement shown in Fig. 1, excludes from the space 45 a 130 large portion of the furnace heat which otherwise would radiate through the rear walls of the two furnaces, this being a feature of importance where the space 45, as in the present instance, forms an ash-removal chamber.

I claim:

1. A wall structure for marine furnaces comprising a supporting framework including a transverse angle member, a fluid cooled panel supported on said framework, said panel comprising upper and lower headers and a series of substantially vertical tubes uniting said headers, means for suspending said tubes and headers from said framework at a point adjacent said upper header, said means comprising a transverse angle member secured to said panel, means for securing said member to the angle member of the framework, and means for preventing transverse displacement of the lower depending portion of said panel while permitting free 140 145 150

expansion of said panel, said means comprising an angle member secured near the lower end of said panel and projecting transversely thereof, said member having secured thereto spaced vertically extending abutment elements and a structural member secured to said framework having a depending portion extending between said abutment elements in slidable relation thereto.

2. In a device of the class described, the combination of a framework, a water wall supported

10 on said framework, said water wall comprising upper and lower headers and a series of substantially vertical tubes uniting said headers, means for suspending said tubes and headers from said

15 framework at a point adjacent the upper header, and means for preventing a transverse displacement of the lower depending portion of said water wall while permitting free expansion thereof, said means comprising an angle member secured

20 to the water wall near the lower end thereof, said member having secured thereto spaced vertically extending abutment elements and an angle mem-

ber secured to said framework having one leg thereof extending between said abutment elements in slidable relation thereto.

3. In a device of the class described, the combination of a supporting framework, a water wall comprising upper and lower headers disposed in substantially the same plane, and a series of substantially vertical tubes uniting said headers, means engaging said tubes at a point adjacent said upper header for suspending said water wall, and means for preventing transverse displacement of the lower depending portion of said water wall while permitting free expansion thereof, said last mentioned means comprising an angle member secured to said tubes near the lower end of said water wall and having secured thereto spaced vertically extending abutment elements and a structural member secured to said framework having a depending portion extending between said abutment elements in slidable relation thereto. 95
